CLAIM

We claim the ornamental design for a dual weapon servicing block, as shown and described.

DESCRIPTION

FIG. 1 is a top perspective view of an embodiment of a dual weapon servicing block, showing the new design;

FIG. 2 is a back side view thereof;

FIG. 3 is a front side view thereof;

FIG. 4 is a left view thereof;

FIG. 5 is a right view thereof;

FIG. 6 is a top view thereof; and,

FIG. 7 is a bottom view thereof.

The broken line disclosure represents portions of the dual weapon servicing block which form no part of the claimed design.
